UNITED STATES PATENT OFFICE.

JOHN WRIGHT, OF HART, MICHIGAN.

FOOT ATTACHMENT.

SPECIFICATION forming part of Letters Patent No. 737,189, dated August 25, 1903.

Application filed June 16, 1903. Serial No. 161,736. (No model.)

To all whom it may concern:

Be it known that I, JOHN WRIGHT, a citizen of the United States, residing at Hart, in the county of Oceana and State of Michigan, have invented certain new and useful Improvements in Foot Attachments; and I do hereby declare the following to be a full, clear, and exact description of the invention, such as will enable others skilled in the art to which it appertains to make and use the same.

My invention relates to an attachment for the foot, the object of which is to provide reliably-efficient means whereby the operator may more easily perform the operation of spading or shoveling the earth or lifting a fork-load or shovelful of any substance which he desires to remove; and with the foregoing object in view my invention consists of certain novel features of combination and construction of parts, the preferred form whereof will be hereinafter clearly set forth, reference being had to the accompanying drawings, which are made a part of this application, and in which—

Figure 1 shows a perspective view of my invention complete as applied to use upon the foot of the operator. Fig. 2 is a plan view of my invention removed from the shoe, showing the strap or securing means by dotted lines. Fig. 3 is a front elevation of my invention as presented in Fig. 2 with the straps removed.

For convenience in designating the various details of my invention and co-operating accessories numerals will be employed, the same numeral referring to a similar part throughout the several views.

Referring to the numerals on the drawings, 1 and 2 indicate branches which comprise the main or body portion of my boot or shoe attachment, said branches being adapted to lie under the sole of the shoe and extend rearwardly to or near the instep portion thereof, while the forward ends of said members are joined together in the substantially disposed U-shaped member 3. The U-shaped member 3 is preferably slightly curved upward and rearwardly toward the instep of the foot, as more clearly shown in Fig. 1, and serves as a means for protecting the toe of the boot or shoe from direct contact with the shovel, fork, or other instrument employed.

I prefer to form upon each side of the U-shaped member 3 the laterally-extending branch 4, the free end of which is slightly curved upward, whereby the recesses 5 on each side of the U-shaped member 3 are provided, said recesses 5 being designed to more effectively co-operate with a fork, as by having the tines thereof rest therein, whereby the fork will be held against lateral movement.

The branches 1 and 2 are connected together by the members 6 and 7, both of which are of sufficient length to extend beyond said members 1 and 2, the free ends thereof being slightly curved downward, as indicated by the numeral 8, whereby the foot will be held against slipping.

In order to removably secure my improved attachment to the foot of the operator, I provide the double ring-like members 9, one ring of which is designed to extend loosely over the curved terminals 8, while the other ring member is designed to receive a suitable lacing-strap 10, as more clearly shown in Fig. 1 and as indicated by dotted lines in Fig. 2. The strap 10 being provided with a suitable buckle 11, it follows that a single strap will be found sufficient, inasmuch as the same may be crossed upon the top of the foot after passing through the double-ring members 9. I also provide the auxiliary strap or heel-engaging attachment 12, which may be permanently connected to one of the ring-like members, as will be readily understood.

It is of course obvious that other means than I have herein described may be employed to secure the attachment to the foot, this part being left to the preference of the manufacturer.

By means of the downwardly-curved terminals 8 the attachment will be found very excellent and efficient as an ice-creeper, whereby the foot of the person will be held against casually slipping in any direction, while the upwardly-curved extension 3, with its laterally-extending branches 4, will prove a great assistance to a person using a shovel or fork, as in digging in the ground where it is desirable to lift and turn a portion of the soil, it being obvious that the curved extensions 8 will take into the soil and prevent the foot slipping away from its position as a ful-

crum for the fork or spade. If preferred, the terminals 8 may be pointed to more reliably insure against slipping.

The various parts of my invention may be cheaply manufactured and readily assembled in their operative positions, and while I have described the preferred combination and construction of parts deemed necessary in carrying out my invention I desire to comprehend in this application all substantial equivalents and substitutes as may be considered as fairly falling within the scope of my invention.

Believing that the construction and manner of using my invention have thus been made clearly apparent, further description is deemed unnecessary.

What I claim as new, and desire to secure by Letters Patent, is—

The herein-described foot attachment comprising the members 1 and 2 terminating at their forward ends in the U-shaped upwardly and rearwardly curved member 3; laterally-extending branches carried by said U-shaped member; connecting-bars uniting the members 1 and 2 and having downwardly-curved terminals and suitable means to removably connect the attachment to the foot whereby a fulcrum-point will be provided upon which to operate a spade, fork or the like, all combined substantially as specified and for the purpose set forth.

In testimony whereof I affix my signature in presence of two witnesses.

JOHN WRIGHT.
